UNITED STATES PATENT OFFICE.

EMIL KASELOWSKY, OF BERLIN, GERMANY, ASSIGNOR TO THE BERLINER MASCHINENBAU ACTIEN-GESELLSCHAFT, VORMALS L. SCHWARTZ KOPFF, OF SAME PLACE.

APPARATUS FOR PUMPING AND COMPRESSING AIR.

SPECIFICATION forming part of Letters Patent No. 395,060, dated December 25, 1888.

Application filed February 4, 1887. Serial No. 226,543. (No model.)

To all whom it may concern:

Be it known that I, EMIL KASELOWSKY, of Berlin, Germany, have invented a new and Improved Air-Compressor, of which the following is a full, clear, and exact description.

The invention relates to that class of air-compressors in which the air is first subjected to an initial pressure before entering the final compression-cylinder; and the object of the invention is to improve the construction of such compressors.

Reference is to be had to the accompanying drawings, forming a part of this specification, in which similar letters of reference indicate corresponding parts in all the figures.

Figure 1 is a longitudinal vertical sectional elevation of a compressor embodying my invention. Fig. 2 is a transverse vertical sectional elevation of the same. Fig. 3 is a plan view. Fig. 4 is a sectional elevation of an improved piston adapted to my air-compressor.

a a are two intake-cylinders, and in which the air receives its initial pressure.

b is the final compression-cylinder. The 25 pistons *d d* of the intake-cylinders *a a* and the piston *l* of the final compression-cylinder, *b*, are mounted on separate piston-rods *d' d' d'*, operated from one and the same cross-head, *c*, which cross-head *c* is operated by any convenient or desired power. By way of example I have shown the cross-head *c* as actuated by the steam-operated piston *A* in a cylinder, *B*, the said steam-piston being provided with two piston-rods, *C*, connected with the cross-head *c*. The said cross-head is also shown as provided with a slide for the wrist-pin of the crank-shaft *D* of the fly-wheel. To the shaft *D*, at the end opposite that carrying the fly-wheel, is connected the valve-rod of the slide-40 valve of the steam or other engine. The fly-wheel is provided with ratchet-teeth on its inner side near the periphery, whereby, with the aid of the lever and dog *E F*, the fly-wheel may be started by hand should the engine stop on the dead-center.

Any other suitable actuating mechanism may be employed, and that shown forms no part of the present invention.

The pistons of the several air-cylinders operate simultaneously in the same direction. 50

The piston *d* of each initial compression-cylinder, *a*, is provided with a valve, *e*, of the puppet variety, or of any other suitable construction, and in each cylinder *a* is arranged a valve, *f*, Fig. 1, which communicates with a channel, *g*, at the side of the final compression-cylinder, *b*, near the bottom, which passage *g* in turn communicates with the bottom end of a coiled pipe, *h*, which extends around all the cylinders and communicates at its upper end with the interior of the cylinder *b* through the medium of the inlet-valve *k* in the valve-box *i* at the top of the said cylinder *b*. An outlet-valve, *m*, is also fitted in the valve-box *i*, and its chamber communicates 65 with the outlet-pipe *n*, which, like the pipe *h*, is coiled around all the cylinders, and is connected with the outlet *o*.

In operation the air is received in the duplicate intake-cylinders *a a*, and, as the pistons 70 in said cylinders are forced upward by the cross-head *c* or other power, the air passes through the suction-valves *e* to the rear of the piston, and upon the downward stroke the air in both cylinders *a a* receives its initial pressure, passes through the valves *f* to the passage or channel *g*, from thence to the pipe *h*, and through the same to the final compression-cylinder, *b*, through the inlet-valve *k*. Upon the next upward stroke of the pistons 75 *d d* the air in the cylinder *b* receives its final pressure and passes through the outlet-valve *m* and the outlet-pipe *n* to the outlet *o*, from whence it passes to a storage-cylinder or to a motor or other place of delivery, as may be 80 desired.

To provide for the cooling of the air during and after the process of compression, I construct the apparatus with a water jacket or tank, *p*, surrounding all the cylinders and the 85 coiled pipe. The water-jacket *p* is preferably supplied with water from a feed-pump, *q*, or other source of supply, which will insure a continual circulation of the water in the tank. To further aid the cooling of the air, I construct the cylinders with ribs *r*, thereby in-

creasing the outer surface of the cylinders while economizing space.

More than two initial compression-cylinders may be provided for each final compression-cylinder, if desired.

By duplicating the initial compression-cylinders a very great amount of air is forced into the final compression-cylinder. The air, it will be observed, as it enters the cylinder *b* from the cylinders *a a* acts on the face of the piston *l*, and thus acts to aid the downward stroke of the pistons, by which stroke, as previously explained, the compression of the air in the cylinders *a a* is effected. By my invention, also, the air is cooled in its passage from the initial compression-cylinder, which is a very desirable result, and in addition the air is cooled in its passage from the final compression-cylinder to the outlet.

The air in the final compression-cylinder becomes very hot and has a tendency to injuriously affect the piston. To resist this action of the heated air, I provide the said cylinder with a piston of special construction, as shown in Fig. 4. It consists of a series of oppositely-placed beveled rings, *t*, made of a special heat-resisting alloy, and beneath the said rings is placed a leather washer, *s*, the whole being pressed downward against an annular collar on the piston near its front end by screwing down the screw cap or plate *w*, whereby the piston will be expanded laterally to occupy the full sectional area of the cylinder.

Having thus described my invention, what I claim as new, and desire to secure by Letters Patent, is—

1. The combination, with the water jacket

or tank *p*, the externally-ribbed initial compression-cylinders, *a a*, open at their upper ends, and the final compression-cylinder *b* within said jacket, a passage, *g*, valves *f*, through which the lower or inner ends of the cylinders *a* communicate with the said passage, pipe *h*, connected with passage *g*, coiled around the cylinders *a b* and leading into the upper closed end of cylinder *b* through an inlet-valve, *k*, an outlet-valve, *m*, also in the upper end of said cylinder *b*, the pipe *n*, leading from valve *M* out through the jacket, the parallel simultaneously-operated piston-rods *d' d'*, having a common cross-head, the pistons *d d*, having inwardly-opening valves and working in the cylinders *a a*, and the piston *l* in the cylinder *b*, substantially as set forth.

2. In an air-compressor, the piston having an adjustable and expansible metallic packing at its front end and a leather collar in rear of and protected from the heat by the said metallic packing, substantially as set forth.

3. The combination, with the rod having a threaded front end and a collar, a leather cup-shaped washer resting against the said collar, a series of expansive packing-rings, *t*, also on said rod, the rear ring being in the cup-shaped washer, and a screw-plate, *w*, screwed upon the threaded end of the rod and clamping the rings and washer between it and the collar on the rod, substantially as set forth.

In testimony whereof I have signed my name to this specification in the presence of two subscribing witnesses.

EMIL KASELOWSKY.
